UNITED STATES PATENT OFFICE.

CHARLES H. MOORE, OF NEW YORK, N. Y.

WATER-CLOSET CISTERNS.

No. 920,365.

Specification of Letters Patent.

Patented May 4, 1909.

Application filed January 23, 1905. Serial No. 242,348.

To all whom it may concern:

Be it known that I, CHARLES H. MOORE, a citizen of the United States, residing at New York city, in the borough of Manhattan, in the county of New York and State of New York, have invented a new and useful Improvement in Water-Closet Cisterns, of which the following is a specification.

The object of this invention is to provide a cistern for water closets or like fixtures that will be simple, reliable and noiseless in its operation.

Another object of the invention is to provide a simple means for operating the cistern valve.

In the accompanying drawings forming a part of this specification Figure 1 represents a central vertical section of the invention. Fig. 2 represents a cross section. Fig. 3 represents a cross section of the device that lifts and opens the discharge valve in the cistern, and is connected to the flush pipe and forms a part thereof.

1 shows a cistern of the usual size.

2 is a valve seat within the cistern and having a shank 3 extending through the bottom of the cistern and secured with a lock nut 4.

5 is the nut that secures the flush pipe to the shank of the cistern valve.

6 is the overflow pipe.

7 shows a disk of the discharge valve on the lower end of the overflow, and 8 is a thin flexible valve held to the under side of the disk 7 by a nut 9. This nut 9 has a concave shaped cross bar of depth enough to allow overflowing water to escape at each side of it and into the flush pipe.

10 is a stem on the cross-bar 9 that guides the valve to its seat through an aperture in the cross-bar made in the valve seat shank 3.

11 is a vessel open at the top and recessed at the bottom to encircle the disk 7, and is of sufficient depth to allow the valve to be lifted some distance from its seat before it comes in contact with the under side of it.

12 is a port in the bottom of the vessel to allow water to enter the vessel.

13 is a cover or valve over the port 12.

15 is a lever having a weighted portion extending across the width of the cistern so as to get an even bearing at each side of the cistern without much friction on the axis of the lever, and to evenly distribute the neces-

sary heft that is required to overbalance the weight of the discharge valve, and get the weight as near the axis of the lever as practicable, and by so doing the desired purpose of sustaining the discharge valve up from its seat without having to raise the said valve more than an ordinary distance from its seat is attained. This weighted portion 15 of the lever is arranged within the cistern so that the heaviest part of it is always on the side of its axis farthest from the outlet valve, and is held in the position above the axis wholly by the weight of the discharge valve and fittings attached thereto, but when the lever 15 is operated by the usual pull or other means, the weighted portion of the lever increases in distance from the vertical line *x* of the axis of its journals 16 for every degree it descends from the said position it is shown in when the discharge valve is closed. Therefore for every degree it drops from the normal position it occupies when the discharge valve is closed, the leverage increases and exerts a greater upward pressure or lifting force on the discharge valve until its heft finally overbalances the weight of the discharge valve and keeps the said valve open while the water is discharging from the cistern. When the cistern is nearly empty, the weight of the water in open vessel 11 will overcome the leverage of the weighted portion of the lever 15 and will automatically close the discharge valve and lift the weighted end of the lever to its normal upper position.

14 represents an arm extending out from the lever 15 and forms a part thereof, and is connected to the discharge valve and overflow pipe 6. This overflow extends through the disk and discharge valve 7 and is carried by the lever when the discharge valve is opened.

16 represents two journals, one at each end of the lever 15, each of these two journals are fitted loosely in a journal box 20 secured at each side of the cistern, so that there will be only a slight amount of friction.

17 shows an arm extending out from the lever 15 in the opposite direction from which the arm 14 extends. This arm 17 rests against the top of the cistern when the discharge valve is fully opened. Instead of operating the lever 15 by a chain or other pull connected to the arm 17, I may use the

following devices. 18 is an adjustable fitting on the upper end of the lifting rod 19. 19 is a rod operating in the flush pipe 33. On the lower end of this rod 19 a blade 34 is 5 screwed (by preference) and is entered into the receptacle 22 through two spaces 35 made in the flange 23 within the receptacle. The flange 23 is to support the end of the blade 34 when it and the rod are put into 10 the flush pipe and prevents the blade from entering the receptacle other than the right position, and after the blade is in place the flange prevents it from turning or in any way getting displaced. The lower edge of the 15 blade 34 rests upon the lever 27. 21 is a branch or inlet in the side of the receptacle 22. 25 is a projection within the branch 21 against which the arm 30 of the lever 27 abuts when the handle is turned a certain 20 distance in lifting the cistern valve, and prevents the lever 27 from being turned completely around. If this arm 30 is not used the flange 23 will prevent the lever 27 from being turned completely around. The lever 25 27 where the blade comes in contact with it, is shaped so, that when the weight of the rod 19 and blade 34 are upon it when the discharge valve is closed the handle 32 will be turned to the same positive angle with the 30 flush pipe at each operation. 28 is a flange on the lever 27, 29 is a washer between the flat surface of the flange 28 and the inner flat surface of the cap 26, and 31 is a spring that abuts against the neck of the cap 26 at 35 one end and against a shoulder on the handle 32 at the other end, and this spring compresses the washer 29 between the flange 28 and the cap and prevents any leakage of water through the opening in the cap that 40 the stem of the lever 27 operates in. 32 is the handle.

There are several small details in the receptacle 22 that could be made different without departing from the spirit of the 45 invention, so I do not wish to be confined to any exact construction.

In operation, when the handle 32 is turned partially around, the lever 27 within the receptacle and connected to the handle lifts 50 the rod 19 and cistern valve and allows the heaviest side of the lever 15 to turn to a position where its heft keeps the cistern valve up from its seat while water is discharging from the cistern. Upon releasing 55 the handle 32, the heft of the rod 19 upon the lever 27 automatically turns the handle 32 to a certain position at each operation, and rests upon and retains it in the said position until the next operation. When 60 water has emptied from the cistern to a certain distance below the top of the open vessel 11, the weight of water in the said vessel in addition to the heft of the cistern valve and overflow, turns the weighted portion 15 65 of the lever back to the position where the

cistern valve is heavy enough to seat itself and also hold the weighted lever 15 in a position above a horizontal line of its axis.

The advantages are simplicity, cheapness and noiselessness in operation.

70

I claim as my invention--

1. In a cistern for water closets and like fixtures, the combination with a tank adapted to normally contain water, a flush pipe, a discharge valve and a seat for the discharge 75 valve communicating with the flush pipe, of a fulcrumed lever, means at one side of the fulcrum of the lever connecting said lever with the discharge valve a fixed weight on said lever located above and on the opposite 80 side of its fulcrum to that on which the discharge valve is located and adapted to be manually lowered and exert increasing force as it is lowered, thereby lifting and independently sustaining the discharge valve off 85 its seat while water is discharging from the tank and non buoyant means operated by the discharging of the water from the tank to automatically raise the weight and seat the discharge valve, substantially as described. 90

2. In a cistern for water closets and like fixtures, the combination with a tank adapted to normally contain water, a flush pipe, a discharge valve and a seat for the discharge valve communicating with the flush pipe, of 95 a fulcrumed lever, means at one side of the fulcrum of the lever connecting said lever with the discharge valve, a fixed weight on said lever located on the opposite side of its fulcrum to that on which the discharge valve 100 is located and adapted to be manually lowered and exert increasing force as it is lowered, thereby lifting and independently sustaining the discharge valve off its seat while water is discharging from the tank and non 105 buoyant means operated by the discharging of the water from the tank to automatically raise the weight and seat the discharge valve, before the water is exhausted from the tank, substantially as described. 110

3. In a cistern for water closets and like fixtures, the combination with a tank adapted to normally contain water, a flush pipe, a discharge valve and a seat for the discharge 110 valve communicating with the flush pipe, of a fulcrumed lever, means at one side of the fulcrum of the lever connecting said lever with the discharge valve a fixed weight on said lever located on the opposite side of its fulcrum to that on which the discharge valve is located and adapted to be manually lowered and exert increasing force as it is lowered, thereby lifting and independently sustaining the discharge valve off its seat while water is discharging from the tank and non buoyant 115 means adapted to exert increasing force as the water is discharging from the tank and thereby automatically raise the weight and seat the valve, substantially as described. 120

4. The combination with a cistern a cis-

tern valve, an overflow pipe, and a lever within the cistern, weighted enough at the opposite side of its axis from where the valve seat is to keep the valve up from the seat, 5 when the weighted portion of the lever is turned to a certain position, of a flush pipe having a means provided within it to lift the cistern valve and turn the weighted portion of the lever to a position where it will keep 10 the said cistern valve open and up from its seat (to allow a full flow of water to the closet) after the handle that lifted the valve is released and until the cistern is nearly empty, the said cistern valve being arranged 15 to automatically return to its normal position without the employment of the handle that opened it, and said handle to be operated without a pull and chain, and without any pull down movement of the lever, substantially 20 as described.

5. The combination with a water closet cistern, a cistern discharge valve, an overflow pipe and a flush pipe, of a means provided in the flush pipe to force the cistern 25 discharge valve from its seat to a position where it will remain open far enough to allow a full flow of water to the closet after the lifting apparatus within the flush pipe has been released and until the cistern is nearly empty, 30 the said cistern valve having a means to automatically keep it open and to automatically return it to its seat without the employment of the handle or contact with the lifting element within the flush pipe that opened it, 35 the handle that opens the discharge valve being managed to lift the said discharge valve without the employment of a chain or pull down movement of the lever, substantially as described.

40 6. In combination with a cistern, a cistern valve, and a flush pipe connected to the cistern valve and arranged to remain empty except at times when the closet is being flushed, of a receptacle made separate from 45 and connected to the flush pipe and having one or two grooves or guide spaces 35 made in the wall of it, a blade 34 within the grooves 35 transverse to the position of the lever 27 and connected to the rod 19, a lever 27 with 50 in the receptacle arranged to operate unconnectedly against the edge of the blade 34 and lift the rod 19 and cistern valve from its seat, a stem on the lever and having a handle attached to operate the lever 27 by, and a cap surrounding the stem and secured to the branch opening in the receptacle.

7. In combination with a cistern, a cistern valve, a flush pipe arranged to be empty at times when the closet is not in use, a receptacle connected to the upper and lower sections of the flush pipe, a cap on an opening in the receptacle, a stem within a passage in the cap, a lever at the end of the stem and arranged to lift the rod 19, and the cistern valve from its seat, a flange 28 on the said

stem within the receptacle, and a spring 31 surrounding the stem within a recess in the cap and pressing outward against the handle to keep the flange 28 compressed against the inner surface of the cap 26.

8. In combination with a cistern, a cistern valve, and a flush pipe connected to the said valve and arranged to remain empty except at times when the closet is being flushed, of a receptacle made separate from and connected to the flush pipe and having one or more places in it to guide a fitting 34 and prevent its getting displaced on the lever 27, a fitting 34 on the rod 19, a lever 27 within the receptacle arranged to operate unconnectedly 80 against the under side of the fitting 34 and lift the rod 19 and the cistern valve from its seat, a stem on the lever and having a handle attached to operate the lever 27 and a cap surrounding it and secured to the branch 85 opening in the receptacle.

9. In a cistern for water closets and like fixtures, the combination with a tank adapted to normally contain water, a flush pipe, a discharge valve and a seat for the discharge 90 valve communicating with the flush pipe, of a fulcrumed lever, means at one side of the fulcrum of the lever connecting said lever with the discharge valve, a fixed weight on said lever located on the opposite side of its 95 fulcrum to that on which the discharge valve is located and adapted to be manually lowered and exert increasing force as it is lowered, thereby lifting and independently sustaining the discharge valve off its seat while 100 water is discharging from the tank and means operated by the discharge of water from the tank to automatically raise the weight and seat the discharge valve, substantially as described.

10. In a cistern for water closets and like fixtures, the combination with a tank adapted to normally contain water, a flush pipe, a discharge valve and a seat for the discharge 110 valve communicating with the flush pipe, of a fulcrumed lever, means at one side of the fulcrum of the lever connecting said lever with the discharge valve, a fixed weight on said lever located on the opposite side of its fulcrum to that on which the discharge valve 115 is located and adapted to be manually lowered and exert increasing force as it is lowered, thereby lifting and independently sustaining the discharge valve off its seat while 120 water is discharging from the tank and means adapted to exert increasing force as the water is discharging from the tank and thereby automatically raise the weight and seat the discharge valve, substantially as described.

11. In combination with a cistern, a cistern valve, and a flush pipe connected to the said valve and arranged to remain empty except at times when the closet is being flushed, of a receptacle made separate from 130

and connected to the flush pipe and having one or more places in it to guide a fitting 34 and prevent its getting displaced on the lever 27, a fitting 34 on the rod 19, a lever 27 within the receptacle arranged to operate unconnectedly against the under side of the fitting 34 and lift the rod 19 and the cistern valve from its seat, a stem on the lever and having a handle attached to operate the lever 27 and a cap surrounding it and secured to 10 the branch opening in the receptacle.
